(57) **CLAIM**

The ornamental design for a device for peeling fruits and vegetables, as shown and described.

DESCRIPTION

FIG. 1 is a front elevational view of the device for peeling fruits and vegetables of the present invention;

FIG. 2 is a rear elevational view thereof;

FIG. 3 is a front view thereof;

FIG. 4 is a rear view thereof;

FIG. 5 is a top view thereof;

FIG. 6 is a bottom view thereof;

FIG. 7 is a left side view; and,

FIG. 8 is a right side view.

Broken lines showing portions of the device for peeling fruits and vegetables are for illustrative purposes and form no part of the claimed design.
